ELECTRICAL ATTACHMENT

Philip E. Hamilton, Beaver Falls, Pa.

Application July 31, 1936, Serial No. 93,710

5 Claims. (Cl. 173—343)

This invention relates to electrical fixtures, and more particularly has reference to a receptacle for an attachment plug.

The receptacles heretofore used have been open to certain serious objections. In the first place, they have been dangerous, in that the insertion of certain objects such as hairpins, screwdrivers, etc., has been possible, and numerous persons have received severe electrical shocks as a result thereof. As a matter of fact, housewives have received shocks while dusting the receptacles, and the surfaces adjacent thereto.

Furthermore, when the wires to which the receptacle is attached are struck by lightning, sparks are discharged from the slots in the receptacle. Also, particularly in certain industrial plants where the atmosphere is heavily laden with dust and other foreign matter, the slots in the receptacles become filled up and clogged by such foreign matter, thus rendering proper contact difficult and presenting the possibility of short circuiting.

And finally, considerable difficulty has been experienced in the previously used receptacles by virtue of the fact that, after a period of use, and due to the wear of either the receptacle or the plug, the jacks of the plug are not securely held within the receptacle.

An object of this invention is to overcome the above objections inherent in the prior devices.

Another object of this invention is to provide a receptacle having features which prevent the possible electrical shocking of persons using the same.

35 Yet another object of this invention is to provide a receptacle affording at all times a tight fit with a plug, and having means to prevent the entrance of dust and other foreign matter to the slots.

40 A further object of this invention is to provide a receptacle having the foregoing characteristics and yet simple and economical in construction and requiring only slight changes from the present conventional type of receptacle.

45 With these and other objects in view, which may be incident to my improvements, the invention consists in the parts and combinations to be hereinafter set forth and claimed, with the understanding that the several necessary elements comprising my invention may be varied in construction, proportions and arrangement, without departing from the spirit and scope of the appended claims.

In order to make my invention more clearly understood, I have shown in the accompanying

drawing means for carrying the same into practical effect without limiting the improvements in their useful applications to the particular constructions which, for the purpose of explanation, have been made the subject of illustration. 5

In the drawing:

Figure 1 is a frontal elevation of one embodiment of a receptacle constructed in accordance with my invention.

Figure 2 is a side elevation of the receptacle 10 shown in Figure 1.

Figure 3 is a sectional view along the line 3—3 of Figure 1.

Figure 4 is a sectional view taken along the line 4—4 of Figure 1. 15

Figure 5 is a cross sectional view along the line 5—5 of Figure 3.

Figure 6 is a view in perspective of the receptacle and the cooperating plug in the process of insertion in the receptacle. 20

Referring more particularly to Figures 1 and 2, the receptacle is composed of a cylindrical body portion 1, which may be of vulcanized rubber or any other appropriate insulating material. At the front end of the body portion 1 an annular flange 2 is provided, and at the opposite end a metallic and threaded ring 3 fits around the body portion. The ring 3 is provided with an inturned skirt 4 which lies against the rear of the body member. 25

The front of the body member 1 is cut away to form a recess 5, the upper portion of the wall of such recess having a slope as at 6. The recess 5 is preferably circular, but in any event the sloping portion 6 is circular, for a purpose later 30 to be described.

Channels 7 and 8, diametrically opposed, extend from the base of the recess 5 to the rear of the body portion. These channels are adapted to receive the jacks of a plug, and there are positioned in the slots contact members 9 and 11, respectively. The contact members 9 and 11 are engaged by the plug jacks when the plug is in operative position. 35

While I have disclosed an embodiment comprising a receptacle which is adapted to be screwed into a permanent socket, it will of course be appreciated that the invention may readily take the form of a permanent receptacle which does not require a socket. However, when using 40 the receptacle in association with a socket, the contact 9 is in electrical communication with the center contact in a socket, and the contact 11 is in communication with the side contact of a socket. As best shown in Figure 3, a disc 12, 45

made of insulating material, fits over the rear of the receptacle and engages the exposed face of the inturned skirt 4. The disc 12 is provided with a slot 13 through which contact 9 extends. 5 A metallic circular and raised cap 14 fits over the disc 12 and over an extension of the contact 9 which projects from the slot 13. A screw 15 is adapted to hold the skirt 4, contact 9, disc 12 and plate 14 in assembled position upon the body member 1. As indicated at 16, the contact 9 is continued and is provided with an aperture through which the screw 15 passes. In view of the contact between the contact 9, plate 14 and screw 15, it will be observed that contact 9 is in 10 communication with the center contact of the socket in which my receptacle is threaded. 15 Contact 11 is bent around the rear of the body member and thence downwardly as at 17 to rest within a recess 18 formed in the side of the body member. It will be noted that the threaded ring 3 engages the portion 11 of contact 11, and likewise engages the side contact of the socket to thereby place contact 11 in communication with the side contact of the socket. 20 25 A central recess 19, preferably square or rectangular in cross section, extends from the base of the recess 5. Recess 19 is provided with shoulders 21 beyond which is a restricted portion 22 extending to the rear of the body portion. There 30 is adapted to fit within the recess 19, and to abut against the shoulders 21, a block 23 having a cross section corresponding to that of recess 19. The block 23 is thereby held against rotation. Of course, in lieu of a recess and block angular 35 40 in cross section, the recess and block may be round and a set screw or other suitable holding means provided. A threaded recess 24 is provided in the end of the block adjacent the rear of the body member, and the screw 15 is threaded therein.

A circular disc 25 is adapted to fit in recess 5 and to rest upon the sloping portion 6 of the recess wall. This permits of ready rotation of the disc 25 with respect to the body portion of the receptacle. Diametrically opposed slots 26 extend through the disc 25. A helical spring 27 has one end embedded in the block 23 and the opposite end embedded in the rear of disc 25, by vulcanizing or any other suitable means. This 50 spring of course resiliently opposes any rotation of the disc 25 with respect to the body portion of the receptacle.

The block 23 and disc 25 are so assembled in the receptacle that the slots 26 are 90° out of 55 alignment with the channels 7 and 8. The spring 27, while resiliently opposing rotation of disc 25, nevertheless does permit rotation of the disc in either direction until the slots 26 register with channels 7 and 8. The strength of the spring 60 65 27 may be varied, but is preferably sufficiently strong for the disc 25 to resist rotation except by the jacks of a plug, and in any event the spring is of course sufficiently strong to return the disc to a position where the slots are out of register with the channels 7 and 8.

The operation of my invention is of course obvious. As shown in Figure 6, a plug 28 provided with contacting jacks 29 is used in the operation of my device. As stated, the slots 26 of disc 25 70 are normally out of register with channels 7 and 8 of the receptacle, and the jacks 29 are initially inserted in the slots 26. The plug 28 is then rotated, in either direction, until slots 26 come 75 into register with channels 7 and 8, and then the plug is further inserted until the plug 28 is in

engagement with the flange 2 of the receptacle. When in this position, the jacks 29 are in engagement with contacts 9 and 11 to close the circuit. It will be noted that the plug is securely held in operative position, not only by the resiliency of contacts 9 and 11 but also by a clamping action on the jacks set up by the disc 25 and spring 27. 5

When it is desired to disconnect the plug, it is withdrawn from the receptacle, whereupon the disc 25 returns to its inoperative position, where the slots 26 are out of register with channels 7 and 8. 10

It will be appreciated that my invention provides a safety device for receptacles, preventing 15 accidental or careless contact with the electrical contacts in the receptacle. By providing a spring 27 of sufficient strength, access to the contacts 9 and 11 can be secured only by the use of a plug, at all other times the channels 7 and 8 being 20 closed. Accidental shocks are thereby prevented.

It will also be observed that this closing of the channels 7 and 8, except when the receptacle is in use, prevents the admission of dust and other foreign matter to the channels. Likewise, it will 25 be noted that by my invention a plug is held more securely in operative position than has heretofore been possible.

An outstanding feature of my invention is the 30 simplicity and economy of construction, and it will be appreciated that only slight changes are necessary in order to convert the conventional type of receptacle to an embodiment of my invention.

While I have shown and described the preferred 35 embodiment of my invention, I wish it to be understood that I do not confine myself to the precise details of construction herein set forth, by way of illustration, as it is apparent that many changes and variations may be made therein, by 40 those skilled in the art, without departing from the spirit of the invention, or exceeding the scope of the appended claims.

I claim:

1. An electrical receptacle comprising a body 45 portion, a pair of channels extending therethrough, an electrical contact member in each channel, a third centrally disposed channel, an anchoring member secured in said third channel, a shutter member having a pair of slots adapted 50 to register with the first two mentioned channels, and resilient means having its ends embedded in said shutter and in said anchoring member, said resilient means being adapted to 55 secure the shutter to the body portion and to normally hold the shutter slots out of register with the channels.

2. An electrical receptacle comprising a body portion, a pair of diametrically opposed channels extending therethrough, an electrical contact 60 member in each channel, a third centrally disposed channel, an anchoring member secured in said third channel and held against rotation therein, a shutter member having a pair of slots adapted to register with the pair of channels, and 65 a helical spring having one end embedded in said anchoring member and the other end embedded in the shutter, said spring adapted to secure the shutter to the body portion and to normally hold the shutter slots out of register with the channels. 70

3. An electrical receptacle comprising a body portion, a pair of channels extending therethrough, an electric contact member in each of said channels, a centrally disposed and shoul- 75 dered channel extending through the body por-

- tion, a block adapted to rest against said shoulder, a shutter member having a pair of slots adapted to register with the channels, a helical spring extending from the block to the shutter and adapted to secure the shutter to the body portion and to normally hold the shutter slots out of register with the channels, a closure member for the end of the body portion opposite the shutter, and means for maintaining said closure member upon the body portion, which means are also adapted to hold the block in engagement with the shoulders of the central channel.
4. An electrical receptacle comprising a body portion, a pair of channels extending therethrough, an electrical contact member in each channel, a third centrally disposed channel, an anchoring member secured in said third channel, a shutter member having a pair of slots adapted
- 5
- 10
- 15

to register with the first two mentioned channels, and resilient means having its ends embedded in said shutter and in said anchoring member to secure the shutter to the body portion and to normally hold the shutter slots out 5 of register with the channels.

5. An electrical apparatus comprising a body portion, a pair of channels extending therethrough, an electrical contact member in each channel, a third centrally disposed channel, a block secured in said third channel, a shutter member having a pair of slots adapted to register with the first two mentioned channels, and a resilient member having its ends embedded in said shutter and in said block to secure the shutter to the body portion and to normally hold the shutter slots out of register with the channels. 15

PHILIP E. HAMILTON.
